UNITED STATES PATENT OFFICE.

ALEXANDER MCLEAN NICOLSON, OF NEW YORK, N. Y., ASSIGNOR TO WESTERN ELECTRIC COMPANY, INCORPORATED, OF NEW YORK, N. Y., A CORPORATION OF NEW YORK:

THERMIONIC TRANSLATING DEVICE.

1,366,411.

Specification of Letters Patent. Patented Jan. 25, 1921.

Application filed February 19, 1916. Serial No. 79,429.

To all whom it may concern:

Be it known that I, ALEXANDER MCLEAN NICOLSON, a subject of the King of Great Britain, residing at New York, in the county of New York and State of New York, have invented certain new and useful Improvements in Thermionic Translating Devices, of which the following is a full, clear, concise, and exact description.

10 This invention relates to thermionic translating devices and more particularly to vacuum tube devices in which the discharge of electrons from a heated cathode to an anode is made to vary in accordance with variations in an electromotive force impressed between the cathode and a third electrode.

Its object is to produce a large output from such a device.

20 A well-known type of thermionic translating device is the so-called audion having three electrode elements, namely, a cathode composed of a heated filament, an anode or plate and an input electrode or grid. When such a device is used, for example, as a telephone repeater, the attenuated voice currents to be amplified and re-transmitted are caused to vary the potential between the filament and grid, thereby superposing high frequency variations on the space current flowing between the plate and filament by virtue of the thermionic emissions from the filament and an external constant electromotive force normally impressed between the said filament and the plate. This superposed high frequency current, or output current, has the same frequency characteristics as the input current.

In the present invention the grid element is omitted, and there are employed two thermionically active or electron emitting electrodes which are located on opposite sides of a dielectric separator, such as a sheet of mica, in an arrangement analogous to that of a condenser. An anode is placed opposite and exposed to the thermionic discharge from each of these electrodes. The varying input electromotive forces are impressed between these two electrodes and serve to vary the passage of electrons from the said electrodes to their respective anodes. The electrodes, in effect, function

as mutual cathode and input elements, each serving as an input electrode for the cathode located on the opposite side of the dielectric separator.

This application is a continuation in part of my application, Serial No. 24,468, filed April 28, 1915.

The invention will be more clearly understood by reference to the accompanying drawing in which Figure 1 shows a fragmentary perspective view of the device of my invention, and Fig. 2 illustrates diagrammatically how such a device may be employed in a circuit to amplify telephonic currents.

In Fig. 1, 3 is a highly evacuated vessel within which are mounted in any suitable manner the anode or plate members 4 and 5, and the two cathodes 6 and 7, which in this case are shown as filamentary in form. Between the cathodes 6 and 7 is a dielectric plate 8 of mica or other suitable material and of sufficient size to prevent any short-circuiting action, due to the passage of electrons from one cathode to the other.

In a typical application of this invention, such as that illustrated in Fig. 2, the filaments 6 and 7 are heated to incandescence by the batteries 9 and 10, respectively, and thus become thermionically active and discharge electrons to their respective anodes 4 and 5. For reasons given below, batteries 9 and 10 should preferably be so poled with respect to the filaments 6 and 7 as to give homologous parts of these filaments the same relative polarities; in other words, terminals 6^a and 7^a should, for example, be connected to the positive terminals of batteries 9 and 10 respectively, while terminals 6^b and 7^b would in consequence be connected to the negative terminals of these batteries. Cathodes 6 and 7 are connected to opposite terminals of the secondary winding 11 of the input transformer 12, the primary 13 of which receives the attenuated currents to be amplified. Cathode 6 is also connected through primary winding 14 of the output transformer 19 and through battery 15 to anode 4. Similarly cathode 7 is connected through primary winding 16 and battery 17 to anode 5. Batteries 15 and 17 are of course so poled as to make anodes 4 and 5

positive with respect to their corresponding cathodes 6 and 7 and are preferably of the same magnitude.

When the equilibrium of the system is 5 undisturbed by any flow of current in the winding 13, it is evident that the two cathodes 6 and 7 will be at the same potential with respect to each other and with respect to their respective anodes 4 and 5.

10 The space currents flowing from the anodes 4 and 5 to the cathodes 6 and 7 will therefore affect the windings 14 and 16 differentially. Furthermore, each point on one filament will lie adjacent a point of the same 15 polarity on the other filament; the potential drop due to the heating current in one filament being compensated for by an equal potential drop in the other. This results in a uniform action between the two filaments throughout their lengths and does away with the necessity of a battery such as is employed in the grid circuit of the ordinary audion to maintain artificially the proper potential difference between the 20 input and cathode elements. Considering now the operation of the device, it is known that a positively charged body located near an electron emitting cathode serves to increase the space current between the cathode and 25 an anode maintained positive thereto, and conversely that a negatively charged body will decrease the space current. Bearing in mind the condenser analogy above pointed out, it will be seen that in the present arrangement the thermionic current from the 30 more negative cathode will be increased by the presence of a positive charge on the cathode located on the opposite side of the dielectric 8, and conversely the current from the less negative cathode will be decreased by the negative charge on the opposite side of the dielectric, these current changes being additive to produce in winding 19 an 35 amplified current having the same frequency characteristics as the currents initially impressed on winding 13.

What is claimed is:

1. A thermionic translating device having two cathodes, each serving as a control electrode for the other.
2. A translating device having two thermionically active electrodes in close proximity to one another and separated by a dielectric.
3. A translating device having a dielectric plate, a thermionically active electrode on each side of said plate and an anode opposite each of said electrodes.
4. A thermionic translating device having two electron emitting electrodes, a dielectric separating said electrodes, each of said electrodes simultaneously serving as an input element and as a cathode.
5. The combination of a line, a thermionic device comprising two heated electrodes

one of which is connected to one side of said line, the other heated electrode being connected to the other side of said line, and electron receiving means associated with said heated electrodes, one of said heated 70 electrodes serving as a control electrode for the electron flow from the other of said heated electrodes.

6. A translating device having a dielectric separator, two thermionically active filaments of similar size and form located symmetrically on opposite sides of said separator, and a heating battery individual to each of said filaments, like poles of said batteries being connected to adjacent terminals of 80 said filaments.

7. A translating device having a dielectric plate, a thermionically active electrode on each side of said plate, an anode opposite each of said electrodes, means for impressing a constant electromotive force between said electrodes and said anodes, and means for varying the electrostatic field between 85 said electrodes.

8. An energy translating device comprising a highly evacuated vessel, two thermionically active electrodes and two anodes within said vessel, an input transformer having one terminal of its secondary winding connected to each of said electrodes and an output transformer having two primary windings said primary windings being connected each to one of said anodes. 90

9. An energy translating device comprising an evacuated vessel, two thermionically active electrodes and two anodes within said vessel, an input transformer having one terminal of the secondary winding connected to each of said electrodes, an output transformer having two primary windings and a secondary winding, and two output circuits each including one of said anodes and one of said primary windings, said output circuits being connected differentially with respect to said secondary winding. 100

10. In a translating device, means for creating two electron streams, an electrode in each of said streams for controlling the electron flow in the other of said streams.

11. In a translating device, means for creating two electron streams, an electron emitting cathode in each of said streams for controlling the electron flow in the other of said streams.

12. A translating device comprising an evacuated vessel, two electron emitting electrodes within said vessel, a dielectric within said vessel, said electrodes being separated from each other by said dielectric. 120

13. A thermionic translating device having more than two electrodes, two of said electrodes being electron emitting, each of said electron emitting electrodes serving as a control electrode for the other. 125

14. A thermionic translating device hav- 130

- ing more than two electrodes, two of said electrodes being heated cathodes each serving as a control electrode for the other, and each of said cathodes being at a lower potential than another of said other electrodes in said device. 5
15. An evacuated vessel containing two cathodes and two anodes and means whereby one of said cathodes serves as a control electrode for the other of said cathodes. 10
16. An evacuated vessel containing two electrodes, two other electrodes between said first two electrodes, and a dielectric sheet between said last two electrodes. 15
17. An evacuated vessel containing two anodes, two cathodes between said two anodes, and a dielectric sheet between said cathodes. 20
18. An evacuated vessel containing electrodes, connections therefor providing a plurality of sets of electron paths, and a dielectric body separating one of said sets from another. 25
19. A thermionic device comprising an anode and a thermionic cathode, a source of voltage connected between said anode and cathode, means for controlling the space current between said anode and cathode, said means comprising a second cathode, and a shield of dielectric material between two of said electrodes. 30
20. An evacuated vessel containing an anode and a thermionic cathode, a source of voltage connected between said anode and cathode, means for controlling the space current between said anode and cathode, said means comprising a second cathode, and means comprising a dielectric substance intercepting a flow of electrons from one of 35 said cathodes to said anode. 40
21. In a translating device comprising a thermionic cathode and an anode, means for creating an electron stream between said anode and cathode, means comprising a heated electrode for controlling said electron stream, and a dielectric body between said heated electrode and said anode. 45
22. An evacuated vessel containing a plu- rality of sets of cathode and anode surfaces, and a dielectric body separating one of said sets from another. 50
23. The combination of a line, a thermionic device comprising two heated electrodes one of which is connected to one side of said line, the other heated electrode being connected to the other side of said line, an anode surface for each of said heated electrodes, and a separate source of direct current between each anode and a corresponding heated electrode. 55
24. A thermionic device comprising a cathode, a control electrode, said cathode and control electrode being of the same form and having corresponding active portions thereof in parallel space relation. 60
25. An evacuated vessel containing two cathodes and two anodes, means for supplying space current between said cathodes and anodes, the drop of potential between one anode and its respective cathode being approximately the same in value as the drop of potential between the other cathode and anode, and means whereby one of said cathodes serves as a control electrode for the other of said cathodes. 65
26. A thermionic device comprising an anode, a cathode and a control electrode, two of said electrodes being filamentary in form, means for supplying current through said filamentary electrodes, said filamentary electrodes being of the same shape and arranged in parallel space relation whereby each point on one is opposite a point of the same polarity and potential on the other. 70
27. A thermionic amplifier comprising a plurality of sets of electron paths, each set comprising cathode, anode and control electrodes, one of said electrodes for one of said sets being positioned and connected to serve as a different one of said electrodes for another of said sets. 75
- In witness whereof, I hereunto subscribe my name this 17th day of February A. D., 1916.

ALEXANDER McLEAN NICOLSON.
